UNITED STATES PATENT OFFICE.

RUFUS DUTTON, OF YONKERS, NEW YORK.

IMPROVEMENT IN HARVESTER-CUTTERS.

Specification forming part of Letters Patent No. **157,591**, dated December 8, 1874; application filed March 9, 1874.

To all whom it may concern:

Be it known that I, RUFUS DUTTON, of the city of Yonkers, in the county of Westchester and State of New York, have invented a new and useful Improvement in the Cutting Device for Harvesting - Machines; and I do hereby declare that the following is a full, clear, and exact description thereof, and of the mode or manner of operation, reference being had to the accompanying drawings, and to the letters of reference marked thereon, and making a part of this specification.

Figure 1 is a plan view, showing a section of the finger-bar and knife, with two fingers connected thereto. Fig. 2 is an end view. Fig. 3 is a vertical section of the same.

Similar letters indicate corresponding parts. This invention relates to a new and improved method of holding down the sections in what is called a removable or detachable section-knife to the under surface of the slot of the finger, so as to make a close shear-cut. This I accomplish by forming a projecting rib in the upper front corner of the cross-bar, over which slides a recess-piece, *e*. This piece is riveted to the knife-section, and has a support extending from the back of the knife and resting upon the finger-bar.

A represents a section of the finger-bar; *B*, the fingers; *C*, the knife-sections; *D*, a round knife-back; *E*, piece bent around the knife-back, and to which the knife-sections are riveted. This piece I term a jacket. *a* is the front end of the jacket, so bent as to form a recess, which slides over the projecting rib on the front edge of the cross-bar; the cross-bar,

in this case, being made by rolling up the front edge of the finger-bar, of which it forms a part. *b* and *c* are nuts for clamping together the sections on the rod *D*, which forms the knife-back. *d* is a projecting tongue formed by turning back part of the jacket. This tongue rests upon the finger-bar *A*, as seen in the drawing, and serves as a bearing to hold down the front end of the section *C*. The sections *C* are each riveted to the jacket-pieces *E*, which are made of the same length as the sections. The section is riveted upon the jacket in such a manner as to form a projection on one end, which interlocks and upholds the adjoining section. *e* shows the recess formed on the front end of the jacket, which recess slides upon the projecting rib *a* of the cross-bar. The fingers are cut away so as not to interfere with the free movement of the projection when the knife is at work. The knife-back in this invention is made of round steel, making it necessary to hold each section by itself down upon the surface of the slot. This I accomplish in the manner described.

What I claim as my invention, and desire to secure by Letters Patent, is—

The projecting rib from the front edge of the cross-bar, in combination with the recess or interlocking piece attached to the knife-section, substantially as described.

RUFUS DUTTON.
